UNITED STATES PATENT OFFICE

CHARLES ERNEST WOLF AND ANTHONY AGLI, OF HACKENSACK, NEW JERSEY

SAMPLE BOOK

Application filed June 1, 1928. Serial No. 282,070.

The present invention relates to sample books for the display of fabric specimens by salesmen to prospective customers and has for its principal object to construct a book of a continuously formed sample or backing machine adapted to be folded into a compact form and providing means at each side of the machine for attaching cards on which the samples of the fabric are mounted so that the same may be folded together with these sheets into the form of a book.

A further object of the invention is to provide the folding machine with a series of apertures for removably receiving the ends 15 of the sample card and providing a series of supplemental card attaching means at opposite sides of the folding machine and secured to the alternate sections thereof and with the edges of said supplemental sheets arranged to form a divider between the ends of the sample cards mounted at the opposite side of the folding means whereby to prevent interference with each other during the mounting and removal of the cards from said 25 apertures.

A still further object is to provide a sample book of this character in which the material entering into the construction thereof is usually a minimum and which utilizes both sides 30 of the folding means for the display of the samples, which is neat and attractive in appearance, relatively inexpensive to manufacture and otherwise well adapted for the purposes for which the same is intended.

Other objects and advantages reside in the special construction, combination and arrangement of the various elements forming the invention as more fully hereinafter described and claimed, reference being had to the accompanying drawings forming a part hereof, wherein like numerals refer to like parts throughout, and in which:

Figure 1 is a plan view of the foldable means showing the manner in which the sample cards are attached in position thereon,

Figure 2 is a plan view of one of the sample cards upon which the fabric specimens are mounted,

Figure 3 is an edge elevational view show-

ing the manner in which the folding sections of the sheet are arranged in association with the cover,

Figure 4 is a transverse sectional view taken through one of the folding sections of the sheet substantially on a line 4-4 of Figure 1, and

Figure 5 is a fragmentary perspective view of the main folding sheet and the supplemental sheet shown in position for attaching thereto.

Referring to the drawing in detail, wherein for the purpose of illustration I have disclosed a preferred embodiment of my invention, the numeral 5 designates the main sheet 65 of a sample book, preferably constructed of substantially heavy paper or light cardboard of continuous formation and creased or folded at spaced intervals throughout its length as shown by the dotted lines 6 whereby to provide a series of foldable sections 7. To one of these sections 7 is secured a supplemental sheet, said supplemental sheet having its opposite side edges turned inwardly toward each other as shown at 9 and disposed in 75 spaced parallel relation with respect to each other, the outer face of said inwardly folded end sections having a gummed coating 10 applied thereto and extending longitudinally throughout the length thereof whereby to 80 provide a suitable attaching means for said sheet.

The sections 7 of the main sheet are provided with one of the supplemental sheets and secured in the manner indicated alternately 85 at opposite sides of the main sheet 5. As clearly illustrated in Figure 5 of the drawing the gummed portions 10 of the supplemental sheet are arranged adjacent the folds thereof so that the edges of the inwardly folded ends 90 9 are free.

These free ends, it will be observed, are interposed between the sections of the main sheet 5 and the supplemental sheet 8. The outer edge of that supplemental sheet which is attached to the outer edge of the terminal section 7 is suitably attached to one end of a folding cover section 11, as for instance by gluing or the like, said cover section being folded intermediate its ends for folding the 100

two portions thereof upon each other with the section 7 of the main sheet 5 folded therebetween as illustrated in Figure 3 of the drawings, the two portions of the cover 11 thus providing an adequate protecting cover for the entire set of sections 7 and supplemental sections 8 when in folded position. The folded sheet and supplemental sheets are provided with a double row of spaced apart vertically extending slotted openings 12, said openings being formed sufficiently close to the side edges of their respective sections or sheets to enable the edge 9 of the sheet 8 to form the divider between the openings of the sections 7 and the openings of the supplemental sheets 8. Adjacent each opening of one of the rows of slotted openings 12 is arranged an oval-shaped opening 16, said oval-shaped opening being disposed between the slotted openings and the adjacent edge of the section or supplemental sheet, each of the sections 7 and said supplemental sheets being similarly provided with such openings.

A series of sample cards 14 are provided at their opposite ends with tabs 15 and 16 respectively and adapted for insertion in the associated slotted opening 12 of the rows of openings so that the body of the sample cards will be supported upon the outer side of the folding sections 7 and supplemental sheets 8 in a horizontal disposed spaced parallel relation as shown in the drawing.

The tab 15 of the sample cards is of sufficient length so that when inserted in one of the slotted openings 12 adjacent the oval shaped opening 16 the tab will be disposed to register with said last named openings. The openings 13 are of sufficient area to permit the finger to be inserted therethrough for engagement with the tab 15 and thus enable the same to be forced outwardly through the adjacent slotted opening 12 in order that the sample card may be lifted and entirely removed when desired.

Upon each of the sample cards 14 is mounted a fabric specimen 17, or other material or article desired to be displayed in the sample book. By reason of the divider formed by the inturned end 9 of the supplemental sheet the tabs 15 and 16 of the sample cards carried by the folding section 7 and the superimposed supplemental section will be separated from each other so as not to cause interference or displacement of the tab at one side of the sheet 5 upon the removal of such tabs at the opposite side thereof.

By providing a series of supplemental sheets, of the character specified and arranged in the manner indicated upon the main sheet 5, both sides of the main sheet may be adapted for mounting a series of sample cards thereon and displayed in an attractive manner without interference by the tabs of the cards disposed at the opposite sides of the sheet.

It is obvious that our invention is susceptible to various changes and modifications in construction without departing from the spirit of the invention or the scope of the appended claims, and we accordingly claim all such forms of the device to which we are entitled.

Having thus described our invention, what we claim as new is:

1. A sample book comprising a continuously formed foldable sheet, a series of supplemental sheets, attached at the opposite sides of said first named sheet in staggered relation and sample card supporting means formed on each of said sheets and arranged to secure the cards in position thereon with the ends of the cards inserted through the sheets, a portion of said supplemental sheets constituting a separator for the inserted ends of the cards carried at opposite sides of the sheets whereby to prevent contact of the inserted ends of the cards with elements rearwardly of the supplemental sheets.

2. A sample book comprising a continuously formed foldable sheet, a series of supplemental sheets attached at the opposite sides of said first named sheets in staggered relation, sample card supporting means formed on each of said sheets and arranged to secure the cards in position thereof with the ends of the cards inserted through the sheet, said supplemental sheets constituting a separator for the inserted ends of the cards carried at opposite sides of the sheets whereby to prevent contact of the inserted ends of the card with elements rearwardly of the supplemental sheets and a cover sheet for said foldable and supplemental sheets adapted to enclose the same in folded position.

3. A sample book comprising a continuously formed foldable sheet, a series of supplemental sheets attached alternately at the opposite sides of the folded sections of said first named sheets, each of said sections having a series of apertures formed therein providing sample card supporting means with the ends of said cards inserted through said apertures and disposed inwardly of the sheets and inwardly extending flaps carried by said supplemental sheets adapted to prevent contact of the inwardly disposed portions of the cards carried by the respective sheets with the openings of the sheets rearwardly thereof.

4. A sample book comprising a continuously formed foldable sheet, a series of supplemental sheets disposed alternately at the opposite sides of the folded sections of said first named sheets, each of said supplemental sheets having their side edges turned inwardly and interposed between the supplemental sheets and the foldable sheets, means for attaching the folded edges of said supplemental sheet to the folded sections of said first named sheet and with the inturned por-

tions of the supplemental sheet freely disposed, a plurality of rows of vertically extending spaced parallel slotted openings formed in each of said sheets and arranged at the opposite sides of the three portions of said supplemental sheets, and a plurality of sample cards having tabs formed at the ends thereof and adapted for insertion in said slotted openings of the respective rows, the cards of each supplemental sheet and the cards of the associated sections of the folded sheet being arranged back to back with the free portion of the supplemental sheet constituting a separator for the tabs of said cards whereby to prevent insertion of the tab in more than one opening.

In testimony whereof we affix our signatures.

CHARLES ERNEST WOLF.
ANTHONY AGLI.
